DESIGN FOR A CAKE OF SOAP

Samuel Ringold, Los Angeles, Calif.

Application August 19, 1935, Serial No. 58,201

Term of patent 3½ years

To all whom it may concern:

Be it known that I, Samuel Ringold, a citizen of the United States, residing at Los Angeles, in the county of Los Angeles and State of California, have invented a new, original, and ornamental Design for a Cake of Soap, of which the following is a specification, reference being had to the accompanying drawing, forming a part thereof.

The figure is a perspective view of a cake of soap, showing my new design.

The bottom surface of the cake of soap is substantially flat.

I claim:

The ornamental design for a cake of soap, as shown and described.

SAMUEL RINGOLD.
